James Hill

UNITED STATES PATENT OFFICE.

JAMES HILL, OF PROVIDENCE, RHODE ISLAND.

IMPROVED MODE OF POINTING TAGS OF SHOE-STRINGS.

Specification forming part of Letters Patent No. 38,309, dated April 28, 1863.

To all whom it may concern:

Be it known that I, JAMES HILL, a citizen of the United States of America, and a resident of the city and county of Providence, and State of Rhode Island, have invented a new and useful Mode of Pointing the Tags of Shoe-Strings; and I do hereby declare the same to be fully described in the following specification and represented in the accompanying drawings, of which—

Figures 1 and 2 are side views of a shoe-string tag pointed in accordance with my invention. Fig. 3 is a longitudinal section of it, it being exhibited in such figures of a much larger size than it is usually made.

A tag is a tube of metal usually affixed to each of the end parts of a shoe-string in order not only to prevent the braid from becoming untwisted or undone at such end, but to render it easy to pass the shoe-string through the lacing-holes of a shoe.

Tags as heretofore made have been cut off square at one end.

In carrying out my improvement I not only cut each tag beveling at one end, but I conify or point it on the end so beveled, the same being in manner as hereinafter set forth.

A in Figs. 1, 2, and 3 is the tag or tube, *a* being the bevel-cut, while *b* shows the part conified or rounded down into a conical form.

In making the tag, I usually cut at its middle and into two equal parts a tube about double the length which I desire the tag to have, the cut not being made across the tag

square, but diagonally. At the same time the cut is made the end of each tag at the cut is to be coned down or conically pointed, this being done by an implement or machine which is so constructed as not only to perform the diagonal cut of the tube, but at the same time to effect the conical reduction or swaying or compression of it necessary to produce a conical point having an elliptical or elongated opening on one side of it.

There is considerable advantage in the above-described new mode of pointing the tag, because by means of the diagonal cut it is made longer than if cut straight across the double blank. This increase of length makes a material saving of metal in every thousand of the tags made in comparison to what would be required in making tags of the same length with what are termed "square ends." Furthermore, the pointing of the tag by swaging or compressing its end about the diagonal cut can be effected to better advantage than with the square-end tag.

I claim—

My improved method of pointing a tag—viz., by cutting it lengthwise at its end and compressing and reducing it tapering or conically, the whole being substantially as represented.

JAMES HILL.
